UNITED STATES PATENT OFFICE.

THOMAS I. RANKIN, OF PHILADELPHIA, PENNSYLVANIA, ASSIGNOR TO
ABRAM COX STOVE COMPANY, OF PHILADELPHIA, PENNSYLVANIA,
A CORPORATION OF PENNSYLVANIA.

DESIGN FOR A COOKING-STOVE.

SPECIFICATION forming part of Design No. 35,457, dated December 17, 1901.

Application filed September 5, 1901. Serial No. 74,486. Term of patent 7 years.

To all whom it may concern:

Be it known that I, THOMAS I. RANKIN, a citizen of the United States, residing in Philadelphia, Pennsylvania, have invented and produced a certain new and original Design for a Cooking-Stove, of which the following is a specification.

My design for a cooking-stove is clearly illustrated in the accompanying drawing, which represents the stove in perspective.

The essential feature of the design is the foliated scrollwork found on the base, oven-door, fire and ash-pit doors, and on the hot-water chamber, the ornamentation covering the entire surface of the side of the stove, as clearly illustrated.

C is the base of the stove, having legs c and an apron c'. On each leg is a foliated-scroll centerpiece, and the apron c' is ornamented by a series of foliated scrolls.

The oven-door C' has a central medallion or shield, and below this medallion are wave-like scrolls extending from a central point and in-

creasing in size toward each edge of the door. The scrollwork on the upper portion of the door is in keeping with that on the lower portion.

The body C² of the stove directly under the fire-door C³ is ornamented as a continuation of the ornamentation on the fire-door, the ornamentation being in the form of foliated scrolls in keeping with that on the oven-door.

The ornamentation on the water-chamber C⁴ is also in keeping with the ornamentation of the oven-door and base.

I claim—

The design for a cooking-stove as herein described and as illustrated in the accompanying drawing.

In testimony whereof I have signed my name to this specification in the presence of two subscribing witnesses.

THOMAS I. RANKIN.
